UNITED STATES PATENT OFFICE.

RANDAL E. TALLEY, OF IRWIN, PENNSYLVANIA.

ENAMELING FURNACE.

Application filed October 19, 1927. Serial No. 227,131.

This invention relates to electrical enameling furnaces, more especially to the rack element employed in supporting the ware in the furnace.

5 Electrical enameling furnaces are customarily constructed with permanent racks comprising bars supported on the furnace wall and having pins projecting upwardly thereon on which table tops, sheet steel stove parts, and the like are supported while the 10 enamel is being fired.

The ware supporting racks are permanently fixed in the furnace and for that reason are not suitable for enameling small irregular 15 shaped pieces such as stove legs which must be placed on enameling racks outside of the furnace and then charged by suitable means as by a charging fork.

In accordance with the present invention I 20 propose to provide means for adapting the standard permanent rack type furnace to the enameling of small irregular shaped pieces by providing removable capping bars which are placed on the pins of the permanent racks to 25 constitute supports for the removable racks which may be placed thereon by the charging fork.

It is among the objects of the invention to provide a furnace structure adapted for use as 30 a standard permanent rack type enameling furnace and which is readily convertible to a removable rack type furnace in accordance with the kind of ware it is desired to fire.

Another object of the invention is to provide 35 a plurality of sectional capping bars which are provided with seats for engaging the pins of the permanent rack and which are longitudinally disposed in groups and arranged in transverse spaced relation to constitute central and end portions for the removable rack 40 members.

Another object of the invention is to provide 45 a charging fork with capping bars to adapt it for handling removable racks carrying the enamel ware into and out of the furnace.

In the accompanying drawings constituting 50 a part hereof and in which like reference characters designate like parts, Fig. 1 is a sectional elevational view of an enameling furnace embodying the principles of this invention; Fig. 2 is a plan view of a charging fork used in connection with the operation 55 of the furnace shown in Fig. 1; Fig. 3 a cross sectional view taken along the line III—

III, Fig. 2; Fig. 4 a plan view of a removable rack; Fig. 5 a longitudinal sectional elevational view of the furnace shown in Fig. 1; and Figs. 6 and 7 are respectively a plan and section of the capping bars utilized in 60 adapting a standard furnace to the use of removable racks.

Referring to Fig. 1 of the drawings the structure therein illustrated comprises the side walls 1 and top 2 of a furnace provided with suitable heating elements 3 and having transverse beams 4 supported on ledges 5 of the furnace wall. Running longitudinally of the furnace chamber is a refractory pier 6 which constitutes a central support for the 70 beams 4. The beams 4 are provided with pins 7 which constitute the supports for the ware which is placed thereon by a suitable charging fork such as is shown in Fig. 2.

The charging fork comprises a plurality of 75 parallel spaced bars 8 having projecting pins 7 thereon similar to the pins shown in Fig. 1 and the bars 8 are so spaced that they register with the spaces between the pins of the furnace so that when the charging fork is projected into the furnace, the bars 8 will lie between the pins 7 and by subjecting the fork to vertical movement to either raise or lower the ware to be heated on the pins 7, the furnace is charged or discharged as the case may 80 be and the charging fork is withdrawn.

It will be understood with reference to Fig. 5 that the permanent rack enclosing the pin members 7 is preferably made of sectional members to prevent buckling and distortion 85 due to expansion and contraction effected by heat.

The subject matter heretofore explained constitutes no part of the present invention since it is descriptive of a standard form of 90 enamel furnace of the permanent rack type which is, as previously explained, suitable for enameling large sheets or table tops and the like.

My invention consists in capping the pins 100 7 of the permanent rack with suitable bars 10 (Figs. 1 and 5) to provide supports for a plurality of removable racks 11 (Figs. 1 and 4) and further in providing similar capping bars for the charging fork of Fig. 2 whereby 105 the racks are placed on the fork, loaded with ware to be enameled, and then charged into the furnace chamber where they are supported on the capping bars 10.

Referring to Figs. 6 and 7, the capping 110

bars are of any suitable shape and provided with tapered openings 13 which need not necessarily project through the bars but are preferably extended through the entire bar section as shown in Fig. 7, to facilitate the coring of the openings since the bars are preferably cast of suitable heat resisting alloy. A plurality of the bars 10 are arranged longitudinally in the furnace in the manner shown in Figs. 1 and 5 and also transversely in spaced relation as shown in Fig. 1 to provide end and central supports for the removable racks 11. As shown in Fig. 3, two sets of bars are longitudinally disposed in spaced relation on the charging fork so that when the latter is projected between the pins 7 of the permanent rack in the furnace, the bars 10 of the fork will lie between the capping bars of the furnace rack whereby the removable racks 11 may be lowered to and from the capping bars in the furnace.

The capping bars may be readily placed in the furnace by tongs and by virtue of their seats readily align themselves with the pin members 7, and the bars are similarly placed on the charging fork whereby the standard permanent type rack furnace is conveniently converted into the removable rack type structure, thus permitting the use of the furnace for the firing of small irregularly shaped articles.

The advantages of such a combined permanent and removable rack type furnace are readily apparent from a consideration of the cost of furnace structures which makes it highly desirable to utilize a single furnace for both large and small articles.

The removable racks 11 shown in Figs. 4 and 5 are of a standard form and comprise double rows of supporting pins which are integrally formed with a supporting band or rim. The racks are adapted to rest transversely of the bars 10 on the charging fork in the order of the arrangement shown in Fig. 5 and when so assembled on the fork, the ware is laid on the pins 7 after which the racks are bodily transferred to the capping

bars 10 of the furnace in the position shown in Fig. 6.

It is obvious that changes can be made in the details of construction of the capping bars and in the manner in which they are employed in the furnace without departing from the spirit of this invention.

I claim:

1. In an enameling furnace the combination with a permanent rack for supporting articles, of a plurality of bars for capping portions of said permanent rack, said bars being removably attached to said rack and being further disposed to constitute supports for removable rack members which are adapted to be charged into the furnace.

2. In an enameling furnace the combination with a permanent rack, comprising a plurality of longitudinal sections provided with pins for supporting articles, of a plurality of capping bars having seats for engaging said pins, said capping bars being arranged in spaced relation on said pins to constitute supports for removable rack members which are adapted to be charged into the furnace.

3. In an enameling furnace the combination with a plurality of longitudinal sections provided with pins for supporting articles, of a plurality of capping bars having seats for engaging said pins, said bars being disposed longitudinally of said furnace and in spaced relation to constitute central and end supports for removable rack members.

4. In an enameling furnace the combination with a plurality of longitudinal sections provided with pins for supporting articles, of a plurality of capping bars having seats for engaging some of said pins, said bars comprising sectional members disposed in longitudinal alignment and in spaced relation transversely of the furnace to constitute central and end supports for removable rack members.

In testimony whereof, I have hereunto set my hand.

RANDAL E. TALLEY.
